PLASTIC SHOE

Nathan R. Glass, Philadelphia, Pa.

Application November 10, 1944, Serial No. 562,845

1 Claim. (Cl. 36—12)

1

The invention relates to footwear, and more especially to boots, shoes, soles and insoles.

The primary object of the invention is the provision of footwear of this character, wherein the entirety thereof is made up from plastic material, or soles and insoles therefor, and the parts thereof are electronically joined, for invisible tacking of the same together, so that the finished product will be fully waterproof, as well as assuring increased wearing quality thereto.

Another object of the invention is the provision of footwear of this character, wherein its upper, sole, insole, heel and tongue will effect a one-piece integral set-up, in the finished product.

A further object of the invention is the provision of a footwear of this character, which is simple in construction, thoroughly reliable and efficient in its completed product, strong, durable, neat in appearance, fully waterproof, comfortable in the wearing thereof, and inexpensive to manufacture.

With these and other objects in view, the invention consists in the features of construction, combination and arrangement of parts as will be hereinafter more fully described, illustrated in the accompanying drawing, showing the preferred and modified forms of construction, and pointed out in the claim hereunto appended.

In the accompanying drawing:

Figure 1 is a perspective view of a shoe of the low style type constructed in accordance with the invention.

Figure 2 is an enlarged fragmentary longitudinal sectional view thereof.

Figure 3 is a fragmentary sectional view showing a continuous fused seam between adjacent portions of the shoe.

Figure 4 is a sectional view taken on the line 4—4 of Figure 3.

Figure 5 is a sectional view taken on the line 5—5 of Figure 3 looking in the direction of the arrows.

Figure 6 is a view similar to Figure 3 showing spot fusing, as a modification thereof.

Figure 7 is a sectional view taken on the line 7—7 of Figure 6 looking in the direction of the arrows.

Figure 8 is a perspective view of a portion of a molded plastic sole for the shoe.

Figure 9 is a perspective view of a high shoe constructed in accordance with the invention.

Figure 10 is a perspective view of boot constructed in accordance with the invention.

Similar reference characters indicate corresponding parts throughout the several views in the drawing.

Referring to the drawing in detail, A designates generally an article of footwear, shown as a low-shoe, which includes an upper, a sole, heel, tongue

and insole, 10, 11, 12, 13 and 14, respectively, which are of the usual or conventional set-up, excepting that all are made from plastic material, molded or otherwise created. The present invention has to do with the joining of these parts or units, one with the other, and in one instance, the meeting areas of adjacent parts are joined by a continuously fused seam 15, which is effected by an electronic sewing machine, not shown, or otherwise, as best seen in Figures 3 to 5 inclusive, of the drawing.

In Figures 6 and 7 of the drawing, there is shown fused spots 16 of tackings, for the joining of the parts 17 and 18, together, this being a slight modification of the invention, and this procedure may be carried forth in constructing the shoe in the seaming set-up therein where it can be advantageously done, and at the same time affording a waterproof character to the said shoe.

20 The upper 10 of the shoe can be variably colored, this being accomplished by introducing coloring dye to the plastic substance.

In Figures 9 and 10, of the drawing, there is shown an example of a high shoe and boot, 19 and 20, constructed as hereinbefore set forth, and in accordance with the present invention.

In Figure 2 of the drawing, the tip 21 is identified by a cross strip or strap formation 22, while the sole 23 has embedded therein tread inserts 24.

What is claimed is:

In a shoe, a plastic sole of usual configuration, a plastic upper with inturned edges positioned upon the said sole, and a plastic insole positioned on the sole with the edges thereof overlapping the inturned marginal edges of the upper, the said inturned marginal edges of the upper being spot fused to the overlapping edges of the insole and also to the sole of the shoe.

NATHAN R. GLASS.
